UNITED STATES PATENT OFFICE

SAMUEL S. SADTLER, OF SPRINGFIELD TOWNSHIP, MONTGOMERY COUNTY, PENNSYLVANIA

WATER SOFTENER

No Drawing.

Application filed January 10, 1927. Serial No. 160,304.

General experience in the use of waters from natural sources for household and similar purposes has established two classifications, namely hard and soft waters.

5 In general, the hardness of waters is attributable to the different salts of calcium and magnesium therein the presence of which in water used for household purposes prevents the formation of lather when soap is 10 employed until after a sufficient amount of soap has been used to effect decomposition of the salt or salts to form precipitates and render the water soft, after which the use of an additional amount of soap produces a 15 lather. This is referred to merely to indicate an objectionable feature in the use of hard waters for household and domestic purposes, to remedy which water softening compositions are quite generally in use.

20 In the use of water softeners for softening water for household purposes, such as bathing or the laundering of clothes, no means has heretofore been provided, as far as I am aware, for determining readily the amount of 25 the water softening composition necessary to be used to effect the softening desired, the degrees of hardness of which may vary.

In the present invention I have provided not only a water softening composition of 30 marked efficiency, but also a composition including means for indicating when a sufficient quantity of the softening reagent has been introduced into water of any degree of hardness to effect softening of the same.

35 The general object of the invention is to provide a water softener of novel composition having increased efficiency to effect softening of waters as compared with compositions heretofore in use.

40 It also is an object of the invention to provide a water softening composition including means for indicating to the user thereof when a sufficient quantity has been introduced into a body of water to effect the desired softening thereof.

A further object of the invention is to provide a water softening composition including not only water softening and indicating constituents as above stated, but also including 50 means having mild antiseptic characteristics

which at the same time are pleasing and fragrant.

To these and other ends my invention comprehends the composition of ingredients as hereinafter particularly specified, or their 55 recognized equivalents, combined in proportions approximating those hereinafter particularly set forth.

Heretofore, in the manufacture of water softeners, manufacturers usually have employed crystallized sodium carbonate or soda crystals, with which have been embodied ingredients for providing a pleasant perfume. The said last mentioned ingredients, however, have had no other purpose than that of 65 providing an agreeable perfume or odor.

In the manufacture of a composition embodying my invention a mild anhydrous alkaline salt such as the sodium or potassium salt of a suitable weak acid or a mixture 70 thereof (in admixture with other suitable ingredients to be hereinafter mentioned) may be employed. Some of the weak acids which may be mentioned are carbonic, phosphoric, 75 etc.

One composition which may be employed in the production of a water softener embodying my invention, and which is the one at present preferred by me, consists of sodium carbonate (Na_2CO_3) and sodium bicarbonate 80 ($NaHCO_3$) 450 parts; phenolphthalein (dissolved in absolute alcohol) 1 part; oil of pine needles (dissolved in absolute alcohol) 9 parts; oil of eucalyptus (dissolved in absolute alcohol) 9 parts. These ingredients may be mixed together and formed into a powder or they may be mixed together with sufficient liquid to form a substance which may be molded into cake or tablet form or they may 85 be mixed together and used in liquid form.

Or they may be mixed together and used in any other preferred form. The sodium bicarbonate is less intense in its alkalinity than the sodium carbonate usually employed in crystalline form, yet its presence increases 90 the efficiency of the composition as a water softening agency.

It is to be understood broadly that I may employ in lieu of the Na_2CO_3 and the $NaHCO_3$ any other suitable reagent which 100

may be known as an equivalent thereof in the water softening art, and for and in lieu of the color reagent, phenolphthalein, I may employ some other colored indicating medium, such as a so-called chrome blue which will 5 produce a distinct color change when the desired intensity of alkalinity of the water has been produced to effect softening thereof by the introduction of the water softening 10 means (sodium carbonate and sodium bicarbonate or their equivalents).

The proportions as above indicated may be varied within reasonable limits without departing from my invention, and while it is 15 preferred that essential oils of the character indicated be employed, their use is not in fact essential to my invention.

An important feature of my invention is the employment of an ingredient mixed with 20 the water softening reagent which, when the water has attained the desired degree of softness, affords a color indication clearly visible to the user and the appearance of which informs such user that the water has reached 25 the required degree of alkalinity or softness. The presence of oil of pine needles and oil of eucalyptus, or both, or other essential oils, is desirable, but the absence thereof will not detract or destroy the efficiency of the 30 composition as a water softening reagent.

In the employment of a water softening composition such as I have disclosed herein, the manifestation of color (light pink) due to the presence of phenolphthalein happens with 35 hydrogen ion concentrations ranging from about 9.0 to 10.0.

In the use of the softener for laundry purposes it is desirable that an indicating reagent be employed, the indicating color of 40 which is blue, but even if phenolphthalein be employed the color or dyeing effect thereof is so slight as to be practicably inappreciable or negligible and therefore not seriously objectionable. For bathing purposes the water 45 softening composition including phenolphthalein in which the indicating color of light pink is entirely satisfactory may be employed.

It will be understood that the use of alcohol 50 for dissolving the color reagent and the essential oils is not obligatory but that the said ingredients may otherwise be incorporated with the water softening reagents.

The water softener embodying my invention 55 may be prepared and used, as I have already suggested, in the form of a powder, and is preferably so prepared and used, but it may be prepared and distributed for use and used in any other form which may be preferred or 60 desired for any particular purpose or reason.

Having thus described my invention, what I claim and desire to secure by Letters Patent is:

1. A composition of matter for the treatment 65 of water including anhydrous water

softening reagents combined with means to indicate when the desired degree of softness of water into which the said composition may be introduced has been attained.

2. A composition of matter for the treatment 70 of water comprising a mild anhydrous alkaline salt of a suitable weak acid as a water softening reagent in combination with a chemical reagent which is adapted, when the composition is placed in water, to indicate 75 when the desired degree of softness has been attained by a change of color therein.

3. A composition of matter for the treatment 80 of water including a mixture of a suitable anhydrous alkaline salt as a water softening reagent and a suitable chemical reagent which, when the mixture is placed in a body of water, is adapted to indicate when the proper degree of softness has been attained by a color manifestation.

4. A composition of matter for the treatment 85 of water including in admixture a suitable anhydrous alkaline salt as a water softening reagent, a suitable color reagent and a suitable essential oil.

5. A composition of matter for the treatment 90 of water comprising a suitable anhydrous alkaline salt of a mild acid as a water softening reagent, phenolphthalein, and a suitable essential oil.

6. A composition of matter for the treatment 95 of water comprising in admixture a suitable anhydrous alkaline salt as a water softening reagent, phenolphthalein, oil of pine needles and oil of eucalyptus.

7. A composition of matter for the treatment 100 of water comprising in admixture anhydrous sodium carbonate and sodium bicarbonate 450 parts as water softening reagents, phenolphthalein 1 part, oil of pine needles and oil of eucalyptus each 9 parts.

8. A composition for the treatment of water 105 including in admixture a suitable anhydrous alkaline salt as a water softening reagent, and a suitable color reagent.

In testimony that I claim the foregoing as my invention, I have hereunto subscribed my name this 6th day of January, 1927.

SAMUEL S. SADTLER.
